DESCRIPTION

FIG. 1 is a perspective view of a deterrent component according to the design;

FIG. 2 is a side view of the deterrent component of FIG. 1; FIG. 3 is a view from the left of the deterrent component of FIG. 1;

FIG. 4 is a view from the right of the deterrent component of FIG. 1;

FIG. 5 is a view from above of the deterrent component of FIG. 1; and,

FIG. 6 is a view from below of the deterrent component of FIG. 1.

1 Claim, 4 Drawing Sheets

FIG. 1

FIG. 2

FIG. 3

FIG. 4

FIG. 5

FIG. 6
